UNITED STATES PATENT OFFICE.

FRANK A. KING, OF YOUNGSTOWN, OHIO.

MULTIPLE-POURING ATTACHMENT FOR LADLES AND THE LIKE.

1,169,653.

Specification of Letters Patent. Patented Jan. 25, 1916

Application filed May 13, 1915. Serial No. 27,778.

To all whom it may concern:

Be it known that I, FRANK A. KING, a citizen of the United States, residing at Youngstown, in the county of Mahoning and State of Ohio, have invented a new and useful Improvement in Multiple-Pouring Attachments for Ladles and the like, of which the following is a full, clear, and exact description, reference being had to the accompanying drawings, forming part of this specification, in which—

Figure 1 is a sectional view showing a portion of a ladle having my attachment connected thereto; Fig. 2 is a section on the line II—II of Fig. 1 with the ladle indicated in dotted lines; Fig. 3 is a detail view showing one of the hangers and the manner of its engagement with the pouring attachment; Fig. 4 is a section on the line IV—IV of Fig. 1; Fig. 5 is an end view of the pouring attachment; and Figs. 6 and 7 are detail views of one of the hangers, the two views being taken in planes at right angles to each other.

My invention has relation to a pouring attachment for ladles and the like, and is designed to provide a multiple pouring device which can be readily attached to an ordinary ladle for the purpose of dividing the stream 30 of molten metal from the nozzle of the ladle into several different molds.

Referring to the accompanying drawings, in which I have shown the preferred embodiment of my invention and which will now be described, the numeral 2 designates the bottom portion of an ordinary ladle having a pouring nozzle 3.

4 designates the usual stopper.

My attachment comprises a metal shell 6 having therein a lining 7 of brick or other refractory material. The lining is formed with a central sprue 8, which registers with the opening of the nozzle 3, and which, at its lower end, communicates with a branch 45 sprue 9. This sprue extends laterally in opposite directions and terminates in two discharge passages 10 and 11, adapted to deliver the molten metal into two different molds. The lining brick 7 is shaped to fit 50 the lower end portion of the nozzle 3 and form a tight joint therewith.

The attachment may be connected to the ladle in various ways. In the drawings, I have shown this as effected by means of

two depending hanger bolts 12 and 13, 55 which are pivoted at their upper ends to bolts 14, screwed into the metal bottom of the ladle. Each of these hanger bolts has an adjustable nut 15, which forms a support for the slotted lug 16, on the end of the 60 shell 6. The under side of the lug 16, which rests on the end of the hanger 12 is rounded, as indicated at 17, so as to permit the bolt to be readily swung outwardly when it is desired to disconnect the attachment. It 65 is normally prevented from such outward movement by the pivoted latch 18, working through a slot 19 in said bolt.

The advantages of my invention will be apparent to those skilled in the art. The 70 attachment permits of slower pouring of the metal, thus giving better products and more solid steel. This slower pouring also permits of the escape of gases from the metal and thus lessens the segregation. In 75 the ordinary ladle, the greater pressure on the stream of molten metal causes splashing on the side of the mold and the formation of scabs. This is avoided by my attachment. The device can be readily adapted to existing ladles and can be quickly removed therefrom, if desired.

While I have shown the attachment as provided with pouring passages or sprues for two separate molds, it will be understood 85 that it may be adapted for more than two molds. It will also be understood that the particular construction of the attachment and the manner of lining it and connecting it to the ladle can be changed, without departing from the spirit and scope of my invention as defined in the appended claims.

My invention is applicable not only to ladles for pouring ingots, but also to ladles and pots for pouring castings generally in 95 sand or other molds.

I claim.

1. A multiple pouring device for ladles, etc., comprising a container or shell having a refractory lining formed with branch 100 pouring passages or sprues arranged to communicate with the nozzle of the ladle and to supply different molds, together with means for attaching the container to a ladle, substantially as described.

2. A pouring attachment for ladles, etc., comprising a metal shell or container having a refractory lining provided with a plural-

ity of outlets and having separate passages or sprues leading from the outlets to the nozzle of the ladle, together with means for attaching the container to a ladle, substantially as described.

- 5 3. The combination with a ladle having a single bottom pouring nozzle, of a pouring attachment adapted to fit said nozzle and having a plurality of pouring passages or sprues which communicate with the nozzle and which are adapted to supply different molds, together with means for connecting the attachment to the ladle, substantially as described.
- 10 4. The combination with a ladle having a single bottom nozzle, of a multiple pouring attachment adapted to fit said nozzle and having a plurality of separate outlets, and means for detachably connecting said attachment to the ladle, substantially as described.
- 15 5. The combination with a ladle having a bottom pouring nozzle, of a multiple pouring attachment adapted to fit the nozzle and having a plurality of outlets, and depending hangers secured to the ladle and supporting and holding the attachment in place below
- 20
- 25

the bottom of the ladle, substantially as described.

6. The combination with a ladle having a bottom pouring nozzle, of a multiple pouring attachment adapted to fit the nozzle and having a plurality of outlets, and depending hangers pivoted to the bottom of the ladle, said hangers and the attachment having a cooperating detachable supporting means, substantially as described.

7. The combination with a ladle having a bottom nozzle projecting downwardly below the bottom of the ladle, of a multiple pouring attachment having a socket portion arranged to make a tight fit with the projecting portion of the nozzle, and means for detachably connecting the attachment to the ladle, said attachment having a plurality of separate outlets adapted to supply different molds, substantially as described.

In testimony whereof, I have hereunto set my hand.

FRANK A. KING.
